UNITED STATES PATENT OFFICE.

AUGUSTUS FRANKLIN THOMPSON, OF HUNTINGTON, WEST VIRGINIA.

INVERTED GAS-BURNER.

No. 861,619.

Specification of Letters Patent.

Patented July 30, 1907.

Application filed May 14, 1907. Serial No. 373,637.

To all whom it may concern:

Be it known that I, AUGUSTUS FRANKLIN THOMPSON, a citizen of the United States of America, and a resident of Huntington, county of Cabell, and State of West Virginia, have invented certain new and useful Improvements in Inverted Gas-Burners, of which the following is a full and clear specification.

This invention relates more particularly to gas burners in which the mantle is suspended in a pendant or inverted position.

The object of this invention is to provide a burner of this character which is extremely simple in construction and neat in appearance and shall produce a very powerful light, and is adapted to both artificial and natural gases.

The invention consists in the special arrangement, disposition and combination of parts hereinafter described, and shown in the accompanying drawings, in which—

20 Fig. 1 is a vertical section taken centrally through the device; and Fig. 2 is a detail perspective view of the mantle support.

Similar letters of reference indicate corresponding parts throughout the several views.

25 The gas supply pipe is indicated at A and to this pipe is attached the valve plug B containing a needle valve C adapted to control the opening D. An adjusting screw E is tapped through the side of the valve plug and has a conical end to engage the rounded top 30 of the needle valve to depress the same to regulate the flow of gas. The valve is held in an open position by the spring F, and is prevented from being displaced by a pin G when the adjusting screw is out of engagement therewith.

35 Suspended from the valve plug and attached thereto preferably by screw-threads is a mixing chamber E formed of two sections h and h' the sides of the two sections being curved and diverged inwardly and away from each other, the lower section h' having a 40 tubular extension I provided with a contracted mouth. The upper section h is provided with openings J and has fitted thereon a slide or damper K of corresponding shape which is also provided with openings to register with the openings J in the top section. The damper 45 is held to its seat by a shoulder upon the valve plug.

Secured to the tubular extension I is the heating tube L, the attaching means being an annular rib i on the extension and an annular groove l in the heating 50 tube, whereby the two parts can be sprung into engage-

ment, the parts being made of thin metal for this purpose. At the bottom or mouth end of the heating tube L is secured a combined mantle support and burner tip M, secured thereto by indentations, as shown in Fig. 1, or by screw-threads as shown plainly in Fig. 2. 55 The burner tip is formed by contracting the mouth of the shade support, as clearly shown.

Intermediate of its ends the heating tube L is provided with an exterior annular rib l' upon which rests the shade holder N, comprising a solid top n and a depending annular flange n' provided with ventilating openings n² adapted to afford relief from congestion of heated products, and supporting screws n³ to hold the shade in position.

In operation the needle valve C and the mixing 65 chamber valve or damper K are adjusted to the quality and quantity of gas to be used; the flow of gas draws into the mixing chamber a suitable quantity of air to form a suitable mixture, being retarded within the mixing chamber by the contracted mouth of the extension of the chamber to allow of proper mixing. The mixture is then forced into the heating tube, where the products are thoroughly heated and expanded forming a combustible product ready for ignition; the mixture is then forced through the contracted end of the 70 burner tip to the flame. By placing the mixing chamber above and in close proximity to the shade holder, the radiation from the top of the shade holder tends to heat the air before being drawn into the mixing chamber.

80 It will be observed that the heating tube is provided with a contracted inlet and outlet, thereby assuring a perfect combustible product, and preventing back flare of the flame and also providing a bright and steady light.

Having thus fully described my invention, what I claim and desire to secure by Letters Patent is:—

90 In an inverted burner, the combination of an adjustable gas inlet and a mixing chamber depending therefrom and provided with a depending tubular extension having a contracted mouth, a depending heating tube telescoping up over said depending extension, means being provided for removably locking the heating tube to the extension, a mantle support and burner tip at the lower end of the heating tube, and a globe support supported on the heating tube.

95 In testimony whereof I hereunto affix my signature in the presence of two witnesses this 6th day of May, 1907.

AUGUSTUS FRANKLIN THOMPSON.
